UNITED STATES PATENT OFFICE.

CHARLES WIRT, OF PHILADELPHIA, PENNSYLVANIA, ASSIGNOR TO CHARLES WIRT AND COMPANY, OF NEWARK, NEW JERSEY, A CORPORATION OF NEW JERSEY.

RHEOSTAT.

No. 895,822.

Specification of Letters Patent. Patented Aug. 11, 1908.

Application filed July 12, 1905. Serial No. 269,324.

To all whom it may concern:

Be it known that I, CHARLES WIRT, a citizen of the United States, residing at Philadelphia, Pennsylvania, have invented a certain new and useful Improvement in Rheostats, of which the following is a description.

The object of this invention is to produce a rheostat which will be constructed of inexpensive materials, by few and simple operations, while producing a result giving large capacity for size and weight and having the characteristics of durability with capacity to stand a high rate of work in proportion to size and weight, and also to withstand a high temperature without injury.

In the accompanying drawings is shown a rheostat which for the sake of clearness omits parts not needed to show the particular construction and method of maintenance.

Also for the sake of clearness is shown a very heavy resistance conductor having few turns and connected to but few contact blocks. Commercial rheostats would have more "steps" or blocks in the commutator and a longer, lighter resistance conductor placed or wound into more turns.

Figure 1 shows a top view of a rheostat embodying the invention, the shaft and handle broken off; Fig. 2 shows a side view of the same; Fig. 3 shows a bottom plan view; and Fig. 4 a mid section through the center line of the central shaft or spindle. Fig. 5 shows one commutator block; a connecting rod, and an envelop or contact clip.

Fig. 6 illustrates rather diagrammatically a reflexed wire having uniform "pitch" or loop spaces. Fig. 7 shows a similar reflexed wire in which the pitch or loop spans measured in the direction of the completed strip continuously decrease, thus giving the effect of increasing resistance per unit of length while retaining the advantage of using an inexpensive material of uniform section and avoiding joints. Fig. 8 shows a plane spiral and illustrates diagrammatically the plan of arrangement of the resistance conductor when coiled into a suitable shape for a round plate (disk) rheostat. Fig. 9 is a view of a modified form of resistance. Fig. 10 is a bottom view, and Fig. 11 is a side elevation of a modified form of envelop.

In all of the several views like parts are designated by the same reference characters. Referring to the rheostat illustrated here-
55 in the general description is as follows:

The rheostat consists of a resistance conductor 1 (formed preferably of a wire reflexed or put into zig-zag shape) wound circularly upon itself like a roll of tape, the turns being separated electrically by two cords or strips 60 2, 3.

With each turn there is slipped over the resistance conductor a sheet metal envelop or clip 4 so as to straddle the resistance; this envelop preferably having an area as large as permissible and not too stiff to lie 65 down on both sides in close electrical contact with the resistance conductor. This extends beyond the flat face of the completed "roll" to serve as a point of attachment for a contact with that section of the resistance. Instead of an envelop straddling the resistance conductor, the clip may be secured to one side, or it may straddle the conductor, but only one end may protrude beyond the supporting body.

Wound with the resistance and separating the turns thereof are the two threads or strips of flexible insulating material 2, 3. These serve as an insulation; also as spacing strips to give the desired external dimension to the 80 "roll." The thickness of these strips would be predetermined, as the temperature limit of any rheostat is generally fixed, and to keep within such limit for a given duty a certain size will be called for as a minimum. In 85 the construction shown, a very light weight of conductor may be used, keeping down the cost of the most expensive item in the ordinary cost of the material; and having predetermined the desirable size of the structure 90 to fill that space with the resistance material disposed in an extended manner, filling the interspace with a material 5 having the qualities of insulation, solidity, and, so far as possible, both heat capacity and heat conductivity. This material constitutes a molded 95 supporting body. There are materials of the description of artificial stone, also insulating materials in use which may be molded in the soft state, pressed into shape, or even 100 poured in a semi-liquid form, which fulfil the requirements.

Having the resistance put into the required form with the contact envelops located as required and extending at one side, it is only required to place these parts on a flat surface or into the bottom of a suitable temporary or permanent case or box, place the commutator bars 6—the sleeve 7 for spindle—the inclosing metal ring—the feet 110

8—8, &c., and fill in a liquid or semi-liquid insulating body to embed all these parts in a block which is later to become solid. Any suitable material for this purpose may be used, but preferably a material which does not require a very high temperature either to liquefy or to harden. A number of patents on plastic compositions describe a great variety of such materials, some of which have 10 good insulating qualities. A gig or form may be used to locate the respective parts in correct relative position while the filling is being applied.

After the completion of the body of the 15 rheostat by the solidification of the insulating block the connection of the resistance sections to the commutator blocks may be completed by placing the wires 9—9. As shown, these wires or rods are held at either end by 20 being forced into slots in the commutator and clips.

The resistance conductor is arranged in the form of a flat spiral as shown in Fig. 8 and the connections 4 are taken at intervals 25 progressively from that conductor. The result of this arrangement is that the conductor and the insulating body in which it is embedded are heated progressively in rings or annular zones, instead of by angular sectors 30 as heretofore in disk rheostats. This results in a more uniform heating and a lower maximum temperature. While the connections 4 are arranged in a spiral the commutator blocks 6 are arranged in a circle, thus 35 enabling the employment of a contact arm pivoted at the center of the disk, which contact arm can be made short if the commutator blocks are located within the innermost turn of the resistance conductor as they preferably are.

Fig. 9 illustrates a form of resistance strip in which the insulating threads 2, 3 form the warp and the resistance wire 1 the weft of a fabric which is woven in the ordinary manner like a tape or ribbon. As in the construction shown the final support and insulation is afforded by a heat resisting body, it is not required that the insulating strips or threads applied to or laid with the 45 resistance conductor should be fire proof or heat resisting. The effectiveness or life of the rheostat would not be reduced by any heat effect that could be produced under commercial conditions on (for example) cotton threads or strips if used as shown.

Figs. 10 and 11 show a modification in which the sheet metal envelop 4 is extended to reach and overlap the end of the commutator block. The rheostat may be wound 60 with a resistance conductor in the form of a flat tape or ribbon. This would sacrifice the binding effect of the wire loops, which embedded in the insulating body act to reinforce the strength of the latter in a way that a 65 smooth flat strip could not.

The commutator is preferably formed of metal segments, each having a hollow central chamber 10, and a projecting foot 11. The central chamber will become filled with the molded supporting material, and will thereby become firmly anchored in place. The projecting foot extends beyond the filling (indicated by dotted line Fig. 4) and is provided with a notch 12, within which the connector is forced. The parts may thereby 70 be held in position without the use of screws or solder. The connectors are outside of the body, as shown, and may be adjusted or removed, as desired, without demolishing the apparatus.

Having now described my invention what I claim as new and desire to secure by Letters Patent is

1. In a rheostat, the combination of a resistance conductor, contact blocks and a hub 85 or support for the moving element, with a molded body of insulation forming the body of the rheostat and in which the resistance conductor, contact blocks and hub or support for the moving element are embedded and mechanically held by the setting or hardening of the molded insulating body around them, substantially as set forth.

2. In a rheostat, the combination of a resistance conductor, contact blocks and a hub 95 or support for the moving element, with a molded body of insulation forming the body of the rheostat and in which the resistance conductor, contact blocks and hub or support for the moving element are embedded and mechanically held by the setting or hardening of the molded insulating body around them, and a metal ring surrounding the body of insulation and held thereon by the setting 100 or hardening of such body, substantially as 105 set forth.

3. A rheostat having a spirally wound resistance, and a commutator inside of the resistance, both resistance and commutator being within a molded supporting body, and 110 radial connections between the commutator and the resistance outside of the body.

4. A rheostat having a spirally wound resistance, and a commutator within the spiral, both being within a molded supporting body, 115 envelops connecting the resistance at intervals within the body and projecting outside of the body, and radial connectors between the envelops and the commutator.

5. A rheostat having a commutator formed 120 of segments mounted within a molded supporting body, a resistance within the body and outside of the commutator, the said commutator having notches in the protruding portion and radial connectors within the 125 notches, the said connectors connecting the resistance.

6. A rheostat having a commutator and a spirally wound resistance within a molded supporting body, envelops connected to the 130

resistance at intervals and projecting outside of the body, the said envelops having notches for engagement with connectors to the commutator.

5 7. A rheostat having a spirally wound resistance and a commutator within a molded body and connections between the commutator and resistance outside of the body.

10 8. A resistance conductor for rheostats, consisting of a reflexed wire having its turns in the same plane and substantially parallel with each other.

9. A spirally wound resistance formed of a reflexed strip of varying pitch.

15 10. In a rheostat, the combination of a spirally wound resistance formed of a reflexed strip and envelops straddling the strip at intervals.

11. In a rheostat, the combination of a 20 spirally wound resistance formed of a reflexed strip mounted within a molded supporting body, and envelops straddling the strip at intervals within the body, the said envelops projecting outside of the body.

25 12. In a rheostat, the combination of a spirally wound resistance formed of a reflexed strip mounted within a molded supporting body, and envelops straddling the strips at intervals within the body, the said envelop having notched extremities which project outside of the body.

13. A resistance for a rheostat consisting of a conductor reflexed in the same plane to

form a zig-zag wire, the turns being substantially parallel with each other and coiled upon itself to the shape of a flat roll or a disk, a body of insulation filling the interspaces within said resistance and forming a supporting and inclosing body adapted to dissipate the heat generated in said resistance.

35 14. A resistance for a rheostat consisting of a wire or strip reflexed or zig-zagged and the pitch or linear space of the loops varying in regular progression in such manner as to 40 cause a progressive change in the length of wire included per unit length of the reflexed strip.

15. A rheostat consisting of a continuous length of resistance wire, the turns being substantially parallel with each other coiled into a flat roll or spiral, taps attached thereto at intervals connecting with a commutator and an inclosing and supporting body of insulation filling the spaces within the volume of said coil and forming therewith a solid body adapted to dissipate the heat produced, and to provide required mechanical support and electrical insulation.

50 55 This specification signed and witnessed 60 this 30 day of June, 1905.
